HEATER

Carl E. Meyerhoefer, Brooklyn, N. Y., assignor to
E. A. Laboratories, Inc., Brooklyn, N. Y., a corporation of New York

Application February 21, 1940, Serial No. 320,036

2 Claims. (Cl. 257—137)

This invention relates to a structurally and functionally improved heat exchange device, capable of use in numerous different associations but primarily intended to be employed in connection with vehicles and especially for the purpose of heating automobiles.

It is an object of the invention to furnish a unit of this character which may be placed in an inconspicuous or concealed location and by means of which the interior of a space will receive an adequate amount of warm air which will be distributed evenly throughout such space.

A further object of the invention is that of constructing a heater which will occupy a minimum amount of space so that, for example, it may be disposed below the seat of a motor vehicle to distribute air to both the forward and rear compartments of the same. It is to be noted, however, that by means of the present invention that even when so disposed, the heater will not interfere with such functioning or adjustment of the seat as may be necessary.

Still another object is that of furnishing a device of this type in which the B. t. u. delivery will be relatively high and which will embody comparatively few parts, each individually simple and rugged in construction; these parts being properly supported against shock and operating over long periods of time with freedom from all difficulties.

With these and other objects in mind, reference is had to the attached sheets of drawings illustrating one practical embodiment of the invention and in which:

Fig. 1 is a plan view of the heater; and

Fig. 2 is a side elevation thereof.

Fig. 3 is a partly sectional plan view, taken generally along the lines 3—3 and in the direction of the arrows as indicated in Fig. 2.

Fig. 4 is a transverse sectional view, taken along the lines 4—4 and in the direction of the arrows as indicated in Fig. 1; and

Fig. 5 is a fragmentary and enlarged sectional view of an electrical connecting element which is preferably associated with the heater.

As illustrated, the heater is relatively thin and wide. Accordingly, it is ideally suited for disposition below the front seat of a motor vehicle or in other situations where relatively small space is available. As illustrated, the air impeller is driven by a motor which is extended beyond the face of the heater. The housing of this motor may, of course, project through an opening in the floor of the motor vehicle if the heater is disposed below the front seat. Like-

wise, adjacent to this opening, further openings may be provided in the floor to permit the passage of pipes or lines which couple the heat exchange element with a source of heated fluid.

5 The unit, as shown, includes a core formed of two similar sections. Each section includes two pairs of tubes 10, both horizontally and vertically spaced from each other. One end of each tube connects to a header 11, and a similar header 12 is connected to the opposite end of the tube. The fluid flows through header 12 in its passage from one set of tubes to the other set of tubes. The header 11 is constituted of two abutting portions having end walls, as has been indicated at 14 so as to define a pair of adjacent chambers, each having an opening 15 through which fluid may enter or flow from the compartments of the header 11.

The tubes 10 are enclosed within a casing conveniently including an upper plate 16 and a lower plate 17. Adequate heat exchange between the air flowing past the tubes and the heated fluid within the latter is assured by employing radially corrugated ribbons or strips of metal 18 which are interposed between the pairs of tubes as well as plates 16 and 17. These strips are, of course, of suitable gauge and metal so that a maximum of heat transfer is assured. Additionally, they will serve to yieldingly support the tubes 10 in that, in applying the plates 16 and 17, sufficient pressure is resorted to, to place the entire core assembly under slight compression.

35 Thus, aside from the fact that a rattling of the parts is prevented and the tubes are supported against damage, air passages are defined which assure ample heating of the air as it flows through the core assembly. Also, at this time it will be noted that such flow occurs axially inwardly and, thence, radially outwardly of the plates throughout the entire diameter of the latter and excepting only those spaces which are occupied by the headers 11 and 12.

In order to secure the plates against movement, sleeves 19 may be employed which are in line with openings in the plates. In turn, through these sleeves, the bodies of bolts may be extended in order to secure the entire unit against displacement with respect to a supporting surface. Strips 20 may additionally be utilized to prevent any tendency of the edge portions of the plates to shift with respect to each other at points at which they are not supported by the sleeves 19.

55 As shown, the lower plate 17 has the circular

portion of its face bulged upwardly as indicated at 21. Consequently, within the lower face a recess is furnished. In contact with the base of the latter, a motor unit 22 may be disposed and this unit may be secured in position as, for example, by bolts 23. The shaft 24 of the motor extends upwardly into the space defined by the semi-circular sections of the core and at this point mounts an air impeller 25, preferably in the nature of a more or less conventional axial type of fan. The motor rotates, of course, in a direction such that air is drawn inwardly through the opening of plate 16 and this air, in striking the upper face of plate 17, is caused to be diverted outwardly through the interstices of the core. It will, of course, be appreciated that such flow is assisted by the deflector furnished by the upwardly bulged portion 21.

In order to provide a guard for the fan 25, and also to furnish a support by means of which the heater may be carried, there is secured to the upper face of plate 16 a pair of bars 26 which extend across the opening of plate 16. Of course, due to the fact that the heater is ordinarily placed in an inaccessible location—such as under the seat—fear need ordinarily not be felt that fingers of some occupant of the vehicle will come in contact with the blades. Even in such case, however, the guard will at least serve to somewhat house the fan element 25.

As shown especially in Fig. 3, the raised portion 21 may actually be continued in the form of a somewhat oval outline. By this expedient, one of the motor leads 27 may be extended through an opening in the base of the raised portion 21 and may be grounded against plate 17 by being secured under the fastening element 28 which secures a clip 29. The second lead 30 conveniently terminates in a plug 31 coupled to a sleeve 32'. Also coupled to this sleeve is a second plug secured to lead 33 which extends through a switch to a source of power supply (not shown). The lead 33 may, as shown in Fig. 4, pass through grommet 34', mounted in the bulged or raised portion 21 of plate 17. Also the sleeve 32' may be enclosed in a tube 32 of dielectric material which is engaged by the clip 29.

In employing a heater of this type and assuming that it is to be disposed below the forward seat of an automobile, the floor boards of the latter may be formed with openings to accommodate first, the motor casing 22; second, the lead 33; third, the tubes 34 and 35 coupled to the openings 15 of the header 11 and fourth, the bolts which pass through the sleeves 19. The tubes or pipes 34 and 35 are, of course connected to the cooling system of the motor, but may be coupled to any other source of heated fluid.

Under these circumstances, fluid will flow through pipe 34 and tubes 10 of one semi-circular section and through the header 12 coupling the same to the second section. Thence, it will flow through the tubes 10 of the other section to the outlet chamber of header 11 and to the return pipe 35. When motor 22 is operated, air will be drawn inwardly and be distributed radially outwardly between the edges of plates 16 and 17. Also, due to the fact that the tips of the blades 25 extend substantially in line with the edge of the opening defined by plate 16, the latter will act as a shroud plate for the fan, thus increasing the volume of flow.

In mounting the heater, it will, of course, be

understood that the bolts which pass through the tubes or sleeves 19 are, for example, secured to portions of the plate edges which are between the headers which extend forwardly and rearwardly from the front seat. Consequently, the air will be distributed as afore brought out and in proximity to the floor of the vehicle which is a much desired result. This air will then rise and evenly warm the entire interior of the space within which the heater is disposed.

As afore brought out, all parts of the heater will be properly cushioned, and thus it is obvious that among others the several objects of the invention, as specifically afore noted, are achieved.

It is apparent numerous changes in construction and rearrangement of the parts might be resorted to without departing from the spirit of the invention as defined by the claims.

I claim:

1. A thin heater for mounting between a vehicle seat and floor, said heater comprising a pair of semi-circular core sections, each section containing two pairs of horizontally and vertically spaced semi-circular tubes, a header having a pair of adjacent chambers secured to ends of said tubes, one header chamber providing for flow into the tubes of one section and the other providing for flow out of the tubes of the other section, a further header diametrically opposite said first mentioned header and mounted between said core sections and adapted to provide a passage from one core section to the other, heat dissipating material surrounding said tubes, plates secured to each side of said cores and adapted to compressibly engage said heat dissipating material, one of said plates formed with a circular opening for housing a fan, the other of said plates formed with an oval indentation, a portion of said oval indentation mounting a motor for driving said fan, the remaining section of said oval being adapted for flush positioning of motor leads, the inward indentation of said oval portion providing an air deflecting means and a housing for a portion of said motor means, the remaining portion of said motor extending beyond said indented plate and adapted for extending through the vehicle floor.

2. A thin heater for mounting between a vehicle seat and floor, said heater comprising a pair of semi-circular core sections, each section containing two pairs of horizontally and vertically spaced semi-circular tubes, a header having a pair of adjacent chambers secured to ends of said tubes, one chamber providing for flow into and the other providing for flow out of said tubes, a further header diametrically opposite said first mentioned header and mounted between said core sections and adapted to provide a passage from one core section to the other, heat dissipating material surrounding said tubes, plates secured to each side of said cores and adapted to compressibly engage said heat dissipating material, one of said plates formed with a circular opening for housing a fan, the other of said plates formed with an indentation, a portion of said indentation mounting a motor for driving said fan, the remaining section of said indentation being adapted for flush positioning of motor leads, the inward indentation providing by its inner face, an air deflecting means extending towards said fan-housing-opening and the outer face of said indentation providing a housing for a portion of said motor.

CARL E. MEYERHOEFER.
